UNITED STATES PATENT OFFICE.

JOHN CHARLESWORTH, OF CHICAGO, ILLINOIS.

STEAM-CONDENSING APPARATUS.

SPECIFICATION forming part of Letters Patent No. 250,203, dated November 29, 1881.

Application filed March 26, 1881. (No model.)

To all whom it may concern:

Be it known that I, JOHN CHARLESWORTH, a subject of Great Britain, residing at Chicago, in the county of Cook and State of Illinois, in the United States of America, have invented 5 a certain new and useful Improvement in Steam-Condensing Apparatus for Steam-Engines, of which the following is a specification.

My invention relates to improvements in 10 steam condensing and economizing attachments for steam-engines in which turbine and propelling wheels inclosed in air-tight chambers and connected to the water-tank and steam-exhaust of an engine operate together 15 so as to condense and save the exhaust-steam, and at the same time heat the water in the tank, the water from the tank furnishing the operating power; and the objects of my invention are, first, to provide an arrangement of 20 turbine and propelling wheels, pipes, and water-tank in a steam-engine, whereby the water from the tank will operate the wheels, and by said operation to be returned to the tank; second, to save and condense the exhaust-steam 25 from an engine by the water from the tank without allowing it to escape; and, third, to heat the water in the water-tank of a steam-engine by means of the exhaust-steam. I attain these objects by the construction, arrangement, and combination of the mechanism illustrated in the accompanying drawings, in 30 which—

Figure 1 is a front-side view of my attachments. Fig. 2 is a top view of the same. Fig. 3 is a view of the propelling-wheel, showing 35 its construction.

Similar letters refer to similar parts throughout the several views.

A represents a water-tank of a locomotive 40 or other engine. It is made in the usual way, and placed in any suitable or convenient place near the boiler, and is air-tight.

B is an iron pipe connecting tank A with air-chamber D, and is for the purpose of conveying the water from A to D.

C is a turbine wheel inclosed in the air-tight chamber D, and revolves therein, the water from tank A through pipe B operating the same.

D is an air-tight chamber or box, made of

iron and attached to the engine in any convenient position below the level of the tank A, so that the water from A will flow into it.

E is a revolving shaft, to which C is rigidly attached and revolving therewith. At one end 55 E has its bearing in F, and at the other it is rigidly attached to the center of cog-wheel G. E passes through D.

F is a bearing for E, and is secured to the engine in any convenient place. 60

G is a cog-wheel on the end of E, and operates in connection with cog-wheel H.

H is a cog-wheel rigidly attached to shaft I, revolving therewith, being operated by its connection with G. 65

I is a revolving shaft passing through the center of the air-chamber N, propelling-wheel M, and cog-wheel H, and is supported by the frame K. At one end it is secured to H, and at the other turns in the bearing O, which is 70 on the side of the chamber N.

K L is an iron frame-work or support for the shaft I. It is secured in any suitable manner to bring the several parts into proper position. One end of L is secured to box or chamber D. 75

M is a propelling-wheel, made in the shape as shown in Fig. 3. It is inclosed in the air-tight chamber N, and is secured in its center to the shaft I, and revolves therewith.

N is an air-tight chamber or box, sufficiently 80 large to allow M to revolve freely therein. It is placed near D, and in such a position as to allow the several parts to work.

P is an iron pipe connecting chamber D with N, and is for the purpose of allowing the water and condensed steam to flow from D to N. 85

R is also an iron pipe. It connects chamber N with the water-tank A, and is for the purpose of conveying the water and condensed steam from N to A. The pipe R is connected 90 to the tank near its top, as shown in the drawings.

S is a bearing and support for shaft I.

T is an iron pipe connecting the exhaust-steam chambers or drum of the steam-engine 95 with the air-chamber D, and is for the purpose of conveying the exhaust-steam into D without allowing it to escape into the air.

All of the several parts are arranged and connected in the manner as shown in Fig. 1, 100

and are secured to the engine in a manner to allow them to work freely.

The manner of operation is as follows: The several parts are attached to the engine, the 5 pipe T to the steam-exhaust. The water from the tank A is allowed to flow into the pipe B, when it will pass into the air-tight chamber D, and will revolve the wheel C and shaft E, thereby turning the wheel G, which, in connection with wheel H, will turn the shaft I, thereby revolving the wheel M. The water in 10 chamber D will be forced by wheel C through pipe P into chamber N, and from thence by M through pipe R back into the tank A. All the 15 time the exhaust-steam from the engine passes through pipe T into chamber D, and coming into contact with the water is condensed and carried into the tank, and in so doing heating the water in the tank. A vacuum will be 20 created in the chambers D and N and connecting-pipes P and R, thereby preventing resistance to the free movement of the water and 25 condensed steam. Suitable regulating-valves may be attached to tank end of pipes B and R, so that the flow of water may be shut off, if desired.

The tank A has the usual connection with the boiler, so as to supply water. This arrangement effects a perpetual condensation of 30 the exhaust-steam, and allows none of it to escape, and at the same time furnishes a supply of heated water in the tank, always ready for use for the boiler, instead of cold water, now uniformly used, thereby preventing the danger 35 of explosion of the boiler from sending cold water into a heated boiler. The steam thus heating the water in the tank purifies it of all

sediment and animal matter, and thereby prevents incrustation in the boiler or boilers.

My device can be used as a perpetual water 40 motive power, if desired, in which case it is supplied at first with water from the same main to set it in motion. After it is started the supply from the main can be shut off and the device will continue to operate. 45

What I claim as new and original, and desire to secure by Letters Patent, is—

1. The combination, in a steam-condensing apparatus, of the turbine wheel C, having shaft E, carrying cog-wheel G, with a propelling-wheel, M, having shaft I, carrying cog-wheel H, whereby the wheel M is revolved and the water and condensed steam propelled, all arranged substantially as shown and described. 50

2. In a steam-condensing apparatus, the propelling-wheel M, in combination with the air-chamber N, having tank-connecting pipe R, whereby the water and condensed steam are forced into the tank A, all arranged substantially as shown and described. 55

3. The combination, in a steam-condensing apparatus, of the tank A, pipe B, exhaust-pipe T, chamber D, turbine wheel C, having shaft E, carrying cog-wheel G, connecting-pipes P R, chamber N, and propelling-wheel M, having 60 shaft I, carrying cog-wheel H, the water from the tank furnishing the operative power, and all arranged substantially as shown and described. 65

JOHN CHARLESWORTH.
